Application September 17, 1931, Serial No. 563,277

9 Claims. (Cl. 178—44)

This invention relates to circuits for controlling transmission in signaling transmission systems, and particularly to wave-controlled circuits for suppressing echoes and preventing singing in 5 two-way signal transmission systems.

An object of the invention is to improve the operating characteristics of long two-way signaling systems employing wave-controlled apparatus for suppressing echoes and preventing singing. 10

Wave-controlled, circuit-control apparatus, commonly called echo suppressors or anti-singing devices, are usually employed in connection with the repeating circuits of a long two-way signaling system to insure that the system transmits in only one direction at a time, so as to suppress echoes, prevent singing, or both. This is usually accomplished by making the circuit-control apparatus responsive to signal transmission in 15 either direction over the system to increase or reduce the attenuation in the repeating paths.

Certain circuits of the above mentioned type in the prior art have been designed to operate in response to transmitted signals to properly vary 20 the attenuation in the repeating paths by varying the output impedance of a vacuum tube or tubes, connected in series or in parallel with the repeating paths through transformers. By this means the attenuation in the repeating path transmitting signals is maintained small so that it transmits the signals freely, while the attenuation of the oppositely directed repeating path is increased to the point where disturbing echoes or reflected currents are effectively suppressed. 25 In such circuits, the maximum difference in attenuation between the conditions of suppression and transmission is limited by the ratio of inductance to resistance of the transformer windings, and the finite value of the vacuum tube 30 impedance, so that in very long transmission circuits the obtaining of the required amount of impedance change necessitates the use of unduly large transformers and vacuum tubes of very low output impedance, which is impracticable from 35 an economic standpoint.

In accordance with the present invention, a wide difference in the amount of the attenuation introduced in the transmission paths between the conditions of transmission and suppression is obtained with echo suppressor circuits of the above mentioned type without resorting to the use of unduly large transformers or vacuum tubes of particularly low output impedance, by utilizing 40 with the variable impedance vacuum tube or tubes suitably designed feed-back circuits. These

feed-back circuits are preferably of the so-called series type, that is, the type in which the feed-back is series connected with the grid circuit of the variable impedance vacuum tube. 5

The exact nature and advantages of the invention will be better understood from the following detailed description thereof when read in connection with the accompanying drawings in which:

Fig. 1 shows diagrammatically a space discharge device having a feed-back circuit of the 10 series type, such as is used in the transmission control circuits of the invention;

Fig. 2 illustrates graphically the operation of the feed-back circuit of Fig. 1;

Figs. 3 and 4 show four-wire echo suppressors 15 embodying different modifications of the invention; and

Fig. 5 shows a signal-controlled anti-singing device embodying other different forms of the invention. 20

Fig. 1 shows a simplified diagram of a vacuum tube circuit having a series feed-back such as is used in the transmission control circuits of the invention. In Fig. 1, a three-electrode vacuum tube 1 having a cathode or filament 2, an anode or plate 3 and a control electrode or grid 4, and the usual filament heating, grid biasing and space current supply batteries, is shown. The plate circuit of the tube 1 is coupled to the grid circuit thereof through the feed-back transformer 5 25 having its primary winding 6 connected across an impedance Z_0 of value Z_0 connected between the plate 3 of tube 1 and the primary winding 9 of the output transformer 10 in the plate circuit of the tube, and its secondary winding 7 connected 30 in series between the grid 4 and the filament 2 of the tube 1. The secondary winding 11 of the output transformer 10 is connected to a load circuit 35 of impedance Z_L . 40

It will be assumed that $a-b-c-d$ is the series aiding connection of the feed-back transformer 5 and of the output transformer 10. The feed-back transformer 5 is assumed to be an unequal ratio transformer having an impedance Z_A for its primary winding and an impedance Z_B for its 45 secondary winding. The feed-back transformer 5 is assumed to have a voltage step-up of r . The secondary winding 11 of output transformer 10 has an impedance of Z_1 and its primary winding 9 an impedance of Z_2 . The impedance connected across the primary winding 6 of the feed-back transformer 5 will be designated as Z_0 . Z_{12} is the mutual impedance between the self impedances Z_1 and Z_2 of the output transformer 10. Let the voltage amplification of the tube 1 be 50 50 55

designated by m and its internal A. C. resistance by R_0 . Then the voltage E across the secondary winding of the output transformer 10 will be

$$E = Z_1 i_1 + Z_{12} i_2 \quad (1)$$

5 where i_1 and i_2 are the currents flowing through Z_1 and Z_2 respectively; and

$$Z_1 i_1 + (R_0 + Z_0 + Z_2 - rmZ_0) i_2 = 0 \quad (2)$$

10 and therefore

$$i_1 = \frac{E(R_0 + Z_0 + Z_2 - rmZ_0)}{Z_1(R_0 + Z_0 + Z_2 - rmZ_0) - (Z_{12})^2} \quad (3)$$

If the output transformer 10 is an ideal transformer

$$i_1 = \frac{Z_2 E}{Z_1(R_0 + Z_0 - rmZ_0)} \quad (4)$$

15 and the impedance Z looking into the transformer 10 in the direction of the arrow is

$$Z = \frac{E}{i_1} = \frac{Z_1}{Z_2} (R_0 + Z_0 - rmZ_0) \quad (5)$$

If the poling of feed-back transformer 5 is reversed, the sign of the rmZ_0 term will change 25 and the impedance looking into output transformer 10 becomes

$$Z = \frac{E}{i_1} = \frac{Z_1}{Z_2} (R_0 + Z_0 + rmZ_0) \quad (6)$$

30 Equation (5) shows that in the circuit of Fig. 1, as the feed-back is increased the impedance Z decreases and passes through zero to a negative value. When the impedance Z_s of the external load is connected to Z , the vacuum tube 35 circuit becomes oscillatory when Z is less than Z_s . If the poling of feed-back transformer 5 is reversed, as shown by Equation (6), the impedance Z increases with the feed-back. These various 40 relations are shown graphically in Fig. 2 where Equation (5) is plotted for positive and negative values of r . Although r , being the turn ratio of the transformer 5, does not physically take on negative values, the expression (rmZ_0) can be 45 made positive or negative by the proper poling of the transformer 5. The graphical diagram of Fig. 2 indicates the possibility of obtaining zero impedance with a circuit such as shown in Fig. 1. Theoretically, the useful impedance change in the circuit of Fig. 1 is from zero impedance to the open-circuit impedance of the transformer 10. If a change from a theoretical zero impedance to the open-circuit impedance of the output transformer 10 is desired, as would be the case in the echo suppressor circuit of Fig. 50 55 3, the tube 1 is made normally transmitting and on operation a rectified negative voltage is applied between its grid and filament so as to annul the feed-back and make the impedance of tube 1 infinite. If a change from the open-circuit impedance of the transformer 10 to a theoretical zero impedance is desired, as would be the case in the echo suppressor circuit of Fig. 4, the tube 1 is made normally suppressed and a positive rectified voltage is applied between its 60 65 grid and filament to reenforce the feed-back and make the tube impedance substantially zero.

Fig. 3 shows a series feed-back circuit, such as illustrated in Fig. 1, utilized in a four-wire echo suppressor of the "series" loss type, for 70 obtaining a wide difference in the amount of attenuation introduced in the signal transmission paths between the conditions of transmission and suppression.

The circuit of Fig. 3 comprises a one-way transmission path EA including the one-way ampli-

fying device 12 for repeating signals in the direction from west to east and a one-way transmission path WA including the one-way amplifying device 13 for repeating signals in the direction from east to west. The transmission paths EA and WA 5 may be connected at their ends in substantially conjugate relation with each other and in energy transmitting relation with the two-way lines (not shown) between which signals, for example, voice currents, are to be repeated, by hybrid coil 10 transformers and associating balancing networks in the manner well-known in the art.

Bridged across the path EA in the output of the amplifying device 12 therein is the input of an echo suppressor circuit ES comprising the space discharge amplifying device 14 and equivalent two-electrode space discharge rectifying device 15 connected in tandem by the transformer 16, and a vacuum tube loss circuit 17 having its output coupled effectively in series with the transmission path WA in the input of the amplifying device 13 therein, by output transformer 10. The loss circuit 17 comprises a three-electrode vacuum tube with a series feed-back circuit, such as illustrated in Fig. 1, the corresponding elements of the circuits being identified with the same characters as used in Fig. 1. The output terminals of the rectifying device 15 are connected respectively to the terminals of a condenser 18 which is connected in parallel with a resistance 19 in the 30 grid-filament circuit of tube 1 in the loss circuit 17.

Another echo suppressor ES', which has circuit elements identical with those of echo suppressor ES just described, has its input bridged across 35 transmission path WA in the output of the amplifying device 13, and its output connected effectively in series with the transmission path EA in the input of the amplifying device 12 therein as indicated in Fig. 3.

40 As both echo suppressor circuits ES and ES' are identical and operate in a similar manner, the operation of the system of Fig. 3 will be clear from the following description of the operation of one echo suppressor, ES, only.

The circuit elements of tube 1, in the loss circuit 17, are chosen so that in the absence of a potential applied across the condenser 18 in the grid-filament circuit, tube 1 is in the transmitting condition. Thus, normally, the primary winding 45 50 55 9 of output transformer 10 is effectively short-circuited through the low impedance space path of tube 1. The impedance Z inserted in the transmission path WA through the output transformer 10 will be quite low (theoretically zero). In this case, the variable impedance tube 1 takes no power from the transmission path WA because it is made to supply its own losses by its feed-back circuit.

When signals are being transmitted over the 60 65 70 amplifying path EA, the main portion of the amplified signal waves in the output of the amplifying device 12 are transmitted directly to the listening subscriber. A small portion, however, of the amplified waves in the output of the device 12 are diverted into the input of the echo suppressor ES. In the echo suppressor ES, the diverted signal waves are further amplified by the amplifying device 14 therein and rectified by the rectifying device 15 coupled to the output of the device 14 by transformer 16. The circuits of 75 the amplifying device 14 and the rectifying device 15 are so arranged that the rectified signal voltage charges the condenser 18 through resistance 19 in such direction as to make the potential of the grid 4 of tube 1 more negative, so as to 75

nullify the effect of the series feed-back circuit associated with that tube and to render the tube 1 inoperative. The primary winding 9 of the output transformer 10 is thereby effectively open-circuited through the high impedance space path of tube 1 connected to its terminals. The effective impedance inserted in series in the transmission path WA by the windings of the output transformer 10 is thereby increased to its maximum value, and by suitable choice of the values of the inductances of the transformer windings, this series impedance may be made such as to effectively suppress that path, preventing transmission thereover of echoes and reflected currents due to the signals transmitted over the path EA.

The resistance 19 is made large so that the charge on the condenser 18, and thus the blocking of the path WA will be maintained for a desired hangover interval after the speech signals cease flowing in the path EA. The hangover in the operation of the echo suppressor is required to allow for the time for the last wave of voice current from the path EA to pass back over the path WA as an echo and arrive at the point where the latter path is blocked by the echo suppressor. The speed with which the condenser 18 discharges, and consequently the effective length of this hangover interval, can be adjusted by changing the magnitude of the resistance 19.

The four-wire echo suppressor circuit of Fig. 4 differs from that of Fig. 3 in that the output of the loss circuit 17 is coupled by the output transformer 10 in shunt of the transmission path to be controlled instead of effectively in series with that path as in the circuit of the latter figure. This requires that in the normal condition the impedance looking from the transmission path to be controlled through the output transformer of the echo suppressor, be infinite in order that the transmission path WA or EA normally be operative to transmit with maximum efficiency. To accomplish this, an additional three-electrode "bias reversing" tube 20 is inserted between the rectifier 15 and loss circuit 17, and tube 1 in the loss circuit 17 is made normally inoperative by a large negative bias supplied to the grid circuit thereof by the voltage drop across resistance 21 in the grid circuit. The grid of the tube 20 is normally at zero potential, so that a high plate current flows through resistance 21. The primary winding 9 of output transformer 10 is thus effectively open-circuited through the high impedance space path of tube 1. When signal currents flow in the path EA, the rectified signal voltage in the output of tube 15 is applied across the condenser 18 and parallel resistance 19 in the grid circuit of tube 20 in such direction as to render that tube inoperative. The plate current flowing through resistance 21 being thus reduced to zero, the negative potential across resistance 21 is removed leaving the grid of the variable impedance tube 1 at the potential E_g supplied by its grid battery. The potential E_g is so selected that when it is alone applied, the tube 1 is rendered operative to function over its most efficient range. Then, the primary winding 9 of output transformer 10 will be short-circuited through the low impedance space path of tube 1, and the impedance Z looking from the transmission path WA through output transformer 10 is reduced to such a low value that the path WA is effectively short-circuited through the secondary winding 11 of output transformer 10 in shunt therewith. The path WA is effectively suppressed by this short-circuiting connection when voice currents are being transmitted over

the transmission path EA. As in the case of the echo suppressor circuits of Fig. 3, the series feed-back circuit associated with the tube 1 enables a wide difference in the amount of attenuation introduced into the transmission path between the conditions of transmission and suppression to be obtained without necessitating the use of unduly large transformers or control tubes of particularly low output impedance.

Fig. 5 shows the invention applied to an anti-singing circuit of the semi-neutral type suitable for use at the terminals of a radio telephone or a long cable telephone system, for example, a submarine cable telephone system. It comprises a transmitting path TA including the one-way amplifying device 22 for amplifying telephonic signals outgoing to the transmitting apparatus of the radio or cable system (not shown), and a receiving path RA including the one-way amplifying device 23 for amplifying signals received from the radio or cable terminal receiving apparatus.

Bridged across the transmitting path TA in the input of the amplifying device 22 through a transformer 24 are the control circuits 25 and 26. Control circuit 25 has circuit elements identical with those of each echo suppressor in the circuit of Fig. 3, and control circuit 26 has circuit elements identical with those of each echo suppressor in the circuit of Fig. 4.

Control circuit 25 comprises the space discharge amplifying device 27 having its input connected across the path TA by transformer 24, the equivalent two-electrode space discharge rectifying device 28 having its input connected to the output of the amplifying device 27 by transformer 29, and a loss circuit 30, similar to the loss circuit 17 illustrated in Fig. 4, comprising a three-electrode vacuum tube 31 with a series feed-back circuit, such as illustrated in Fig. 1. The input circuit of tube 31 includes a series condenser 32 and a resistance 33 in parallel therewith, the terminals of which are connected across the output terminals of the rectifying device 28. The output circuit of tube 31 is connected effectively in shunt of the path TA in the output of the amplifying device 22 therein by output transformer 34.

Control circuit 26 comprises the space discharge amplifying device 27 having its input connected across a transmission path TA by transformer 24, the equivalent two-electrode space discharge rectifying device 28 having its input connected to the output of amplifying device 27 by transformer 29, the three-electrode "bias reversing" tube 35 including in its grid-filament circuit the series condenser 32 in parallel with the resistance 33, the terminals of which condenser and resistance are connected across the output terminals of the rectifying device 28, and the loss circuit 36 comprising the three-electrode space discharge tube 37 with a series feed-back circuit such as illustrated in Fig. 1, having its grid-filament circuit coupled to the plate-filament circuit of tube 35 by coupling resistance 38. The output circuit of tube 37 is connected effectively in shunt with the receiving path RA in the input of the amplifying device 23 therein by output transformer 39.

Bridged across the receiving path RA in the output of the amplifying device 23 is the input of a control circuit 40 comprising the three-electrode space discharge amplifying device 41 having its input connected across the path RA, the equivalent two-electrode space discharge rectifying device 42 having its input connected to the output of the amplifying device 41 by transformer 75

43 and having its output connected across condenser 44 and parallel resistance 45 in series in the grid-filament circuit of the amplifying device 27 common to control circuits 25 and 26.

5 The tube 31 in loss circuit 30 is biased so as to be normally transmitting, and thus the primary winding of output transformer 34 is normally effectively short-circuited through the low impedance space path of tube 31. The impedance looking from the path EA through the output transformer 34 is thereby theoretically zero, so that the transmitting path EA is normally short-circuited through the secondary winding of output transformer 34. Therefore, it is seen that the control circuit 25 normally acts to disable the transmitting path EA in the output of amplifying device 22.

10 The variable impedance tube 37 in loss circuit 36 is normally suppressed by the high negative bias from the voltage drop across resistance 38 in its grid circuit. The grid of the bias reversing tube 35 is normally at zero potential so that a high plate current flows in resistance 38. Thus, the primary winding of output transformer 39 is 15 effectively open-circuited through the high impedance space path of tube 37. Therefore, the impedance looking from the path RA through output transformer 39 is substantially infinite so that the control circuit 26 has little or no 20 effect on the transmission of signals over the path RA.

25 The operation of the system of Fig. 5 will now be described. Let it be assumed that signal waves to be transmitted are being sent over the transmitting path TA. These waves will be divided between the input of the amplifying device 22 and the input of control circuits 25 and 26. The portion diverted into the control circuits 25 and 30 26 will be amplified by the amplifying device 27 and rectified by the rectifying device 28 common to the two control circuits. The rectified signal voltage in the output of the rectifying device 28 will be impressed across the condenser 32 and parallel resistance 33 on the input electrodes of the tube 31 in control circuit 25, and on the input 35 electrodes of the amplifying device 35 in control circuit 26, respectively. The rectified signal voltage charges the condenser 32 through resistance 33 in such a direction as to make the potential of 40 the grids of tubes 31 and 35 more negative. The effect of this on the tube 31 is to nullify the effect of the associated feed-back circuit and to render the tube 31 inoperative. The primary of output 45 transformer 34 is thereby effectively open-circuited through the high impedance space path of tube 31 connected between its terminals. The impedance looking from the path TA to the output transformer 34 is thereby increased from its normal theoretical zero value to such a high value 50 as to effectively remove the short-circuiting disabling connection from that path. Thus, the control circuit 25 is ineffective to prevent transmission of the amplified signal waves from the output of the device 22 to the radio or cable transmitting apparatus.

55 The rectified signal voltage across condenser 32 and parallel resistance 33 throws the grid of tube 35 so far negative as to render that tube inoperative. The plate current of that tube being 60 thus reduced to zero, the negative potential applied across resistance 38 is removed, leaving the grid of the variable impedance tube 37 at the fixed potential E_a supplied by its grid battery. The potential E_a is selected so that when it is alone 65 applied, the variable impedance tube 37 is ren-

dered operative over its most efficient range. The primary winding of output transformer 39 is thereby effectively short-circuited through the low impedance space path of tube 31. This causes the impedance looking from the receiving path RA through the output transformer 39 to be decreased from its normal infinite value to a value of zero theoretically, thereby inserting such a loss in the path RA through the bridging connection of the secondary winding of output transformer 39 thereto as effectively to suppress the path RA. Thus, incoming waves thereafter received from the radio or cable receiving apparatus are prevented from reaching the input of the amplifying device 23.

10 The resistance 33 is made of suitable value so that the charge on the condenser 32 is maintained for a desired hangover interval to prevent the transmitting path TA from being prematurely blocked and the receiving path RA from being 15 prematurely rendered operative when the supply of signals to control circuits 25 and 26 ceases.

15 Preferably receiving path RA should be suppressed in response to the signals transmitted over the transmitting path TA in the manner just described simultaneously with or before the transmitting path RA has been rendered operative to transmit the amplified signals to the radio or cable transmitting apparatus. To accomplish this, it may be necessary to insert in the control circuit 25 a delay circuit or to utilize other suitable means for producing a lag in the operation of the loss circuit 30 with respect to that of the loss circuit 36 in response to the rectified signal voltages impressed upon their respective inputs. 20 To prevent a loss of part of the speech transmitted over the path TA, it may be necessary in some circuits to insert a delay circuit of suitable design in that path between the point of connection thereto of the input of control circuits 25 and 26 25 and the point at which the output transformer 34 is connected thereto, to insure that the path TA is rendered operative before the amplified signals reach the point in that path which is normally 30 blocked by control circuit 25.

25 The operation of the system, when signal waves are being received in the receiving path RA from the radio or cable receiving apparatus, and outgoing signals are not being transmitted over the transmitting path TA, is as follows:

30 The control circuit 26, being normally in such condition as to have no appreciable effect on the transmission of waves over the path RA, the received signals will be transmitted to the amplifying device 23 and amplified thereby. The main portion of the amplified signals in the output of the amplifying device 23 will be transmitted over the path RA to the listening subscriber. A portion of the amplified waves, however, will be 35 diverted into the control circuit 40 and will be 40 amplified in the amplifying device 41 therein. The amplified waves in the output of the amplifying device 41 will be rectified by the rectifying device 42 and impressed on the condenser 44 and parallel resistance 45, in the grid-filament circuit of the amplifying device 27 common to the control circuits 25 and 26, in such direction as to 45 throw the grid of the device 27 so far negative as to prevent its operation by signal waves subsequently impressed on the input circuit thereof from the path TA. Thus, subsequent false operation of control circuits 25 and 26 is prevented. On cessation of transmission of received waves 50 over the path RA, the condenser 44 will discharge 55

through the resistance 45 thus holding the amplifying tube 27 inoperative for a definite hangover period, which period may be adjusted to any desired value by proper choice of the value of the 5 resistance 45. At the end of this period, the amplifying tube 27 will be returned to its normal condition so that it will be rendered operative by any subsequent speech waves transmitted over the path TA.

10 In the same manner as explained in connection with Figs. 1 to 4, in accordance with the invention, the series feed-back circuits associated with tube 31 in loss circuit 30, and with tube 37 in loss circuit 36, respectively, will cause a very wide 15 difference in the amount of attenuation introduced in the transmission paths TA or RA respectively, between the conditions of suppression and transmission.

Certain tests which have been made indicate 20 that as much as 40 decibels loss can easily be produced by circuits of the type shown in Figs. 1, and 3 to 5 inclusive in signal transmission paths, over a range from 200 to 3,000 cycles per second. This high loss is made possible by giving the feed- 25 back impedance, indicated as Z_0 in Fig. 1, such a value that it will compensate for the non-ideal characteristics of the feed-back transformer 5 and output transformer 18. A comparatively simple network was found to be sufficient to cause 30 as much as 40 decibels loss in a 600 ohm circuit.

It will be obvious that the general principles 35 herein disclosed may be embodied in many other forms and arrangements without departing from the spirit and scope of the invention as defined in the appended claims.

What is claimed is:

1. In a transmission system, a signal transmission circuit, an electric space discharge device having an input and an output circuit, means 40 inductively coupling the output circuit of said device to said transmission circuit so as to place an alternating current impedance in said transmission circuit which controls transmission therein, said impedance normally having a certain 45 value, means for impressing a potential on said input circuit of said device so as to change said alternating current impedance in said transmission circuit to a different value, and means for effectively increasing the difference between the 50 value of the normal alternating current impedance in said circuit and that of the changed impedance therein, the last mentioned means comprising a circuit for feeding back in proper phase relation energy from the output to the input circuit of said device.

2. In combination in a signal transmission system, a signal transmission circuit, an electric space discharge device having a cathode, anode and a control electrode, and circuits therefor, the cathode-anode circuit of said device being inductively coupled to said transmission circuit so as to place an alternating current impedance in said transmission circuit which controls transmission therein, said impedance normally having a certain 65 value, means for applying a biasing potential to said control electrode such as to change the value of said alternating current impedance in said transmission circuit, and means for effectively increasing the difference between the normal and changed value of said alternating current 70 impedance in said transmission circuit, comprising a circuit for feeding back in proper phase relation energy from the cathode-anode circuit of said device to its grid-cathode circuit.

75 3. The system of claim 2 and in which the feed-

back circuit is series connected with the grid-cathode circuit of said device.

4. The system of claim 2 and in which said alternating current impedance in said transmission circuit is produced by connecting the cathode-anode circuit of said device effectively in shunt with said transmission circuit through a transformer, and the feed-back circuit is series connected with the grid-cathode circuit of said device. 10

5. The system of claim 2 and in which said alternating current impedance in said transmission circuit is produced by connecting the cathode-anode impedance of said device effectively in series with said transmission circuit through a 15 transformer.

6. The system of claim 2 and in which the feed-back circuit comprises a transformer having its primary and secondary windings respectively connected in series with the anode-cathode circuit 20 and the grid-cathode circuit of said device.

7. In a signal transmission system, two one-way transmission paths for transmitting in opposite directions, a three-electrode vacuum tube having its plate circuit effectively connected in series with one of said paths through a transformer, said tube being normally operative so that its plate impedance produces such a low loss in said one path that it transmits signals freely, means responsive to signals transmitted over the 30 other of said paths to bias the grid of said tube to render the tube inoperative and thus increase the loss in said one path to the point where said one path is substantially disabled for transmitting signals, and means for increasing the difference 35 between the values of impedance effectively inserted in said one path in the operative condition and the disabled condition of said one path, the last mentioned means comprising a circuit for feeding back in proper phase relation a portion 40 of the output energy of said tube from said plate circuit to the grid circuit of said tube.

8. In a signal transmission system, two one-way signal transmission paths for transmitting in opposite directions a three-electrode vacuum tube 45 having its plate circuit effectively connected in shunt with one of said paths through a transformer, said tube being normally inoperative so that its plate impedance effectively inserts in shunt with said one path an impedance of such 50 high value that said one path transmits signals freely, means responsive to transmission of signals in the other of said paths for applying a biasing potential to the grid of said tube to render said tube operative and thus reduce the value of 55 the impedance in shunt with said one path to the point where said one path is substantially disabled from transmitting signals, and means for effectively increasing the difference between the values of impedance inserted in shunt with said one path in its operative and disabled conditions, the last mentioned means comprising a circuit for feeding back in proper phase relation energy 60 from the plate circuit to the grid circuit of said tube.

9. In a signal transmission system, two oppositely directed one-way signal transmission paths, two three-electrode vacuum tubes each having its plate circuit connected effectively in shunt with a different one of said paths, one of said tubes being normally operative so that the impedance effectively inserted thereby in shunt with the associated one-way path is of such low value as to effectively disable that path, the other of said tubes being normally inoperative so that 75

the impedance inserted in shunt with the associated one-way path is of such high value as normally to allow said other path to transmit signals freely, means responsive to transmission of signals in the first one-way path to apply a biasing potential to the grid of said one tube to render it disabled thus increasing the impedance effectively inserted thereby in shunt with said first path to such a high value as to render said first path operative, and to apply a biasing potential to the grid of said other tube to render it operative and thus reduce the value of the impedance effectively inserted thereby in shunt with said other

path to the point where said other path is effectively disabled, means responsive to signals transmitted over said other path to disable the means for applying biasing potential to both tubes, and means for effectively increasing the difference between the values of the impedance inserted in shunt with each transmission path by the associated vacuum tubes in the operative and disabled condition of the path, the last mentioned means comprising a circuit for feeding back in proper phase relation energy from the plate circuit to the grid circuit of each tube. 5 10
